ANTON PASIERBSKI, OF MIKULTSCHÜTZ, GERMANY.

IGNITING DEVICE FOR MINERS' LAMPS.

1,091,891.

Specification of Letters Patent.

Patented Mar. 31, 1914.

Application filed September 28, 1911. Serial No. 651,861.

To all whom it may concern:

Be it known that I, ANTON PASIERBSKI, a citizen of the German Empire, and residing at Mikultschütz, Silesia, German Empire, 5 have invented a certain new and useful Improved Igniting Device for Miners' Lamps, of which the following is a full, clear, and exact description.

The present invention consists of an im- 10 proved igniting device for miners' and other closed safety lamps and of the details of construction hereinafter set forth and par- ticularly pointed out in the claim.

The present igniting device comprises a 15 spring pressed pyrophoric body such as ceric iron and a roughened steel surface, adapted to be moved over the said body from the exterior of the lamp, by hand, and, when re- leased, to be rapidly returned to its initial 20 position, by means of a spring or its equiva- lent, the friction thus caused between the steel surface and the pyrophoric body, gen- erating a spark, which ignites the lamp. The 25 device may be modified according as to whether it is to be used in connection with gas (acetylene or the like) or benzin lamps.

The figure of the accompanying drawing shows an embodiment of the invention, suit- able for an acetylene gas lamp.

30 In the device illustrated, a segment shaped or curved plate *l*, having a roughened surface to contact with the pyrophoric body *i*, is linked to the upper end of a double arm lever *o* pivotally supported in the housing 35 at *q*, the said plate being guided between a stationary pin *m* and the spring pressed pyrophoric body *i*. The arm or plate *l* is advantageously bent to a curve or arc struck from the center *q* of its pivot. The lower 40 end of the lever *o* is in detached engagement with a spring pressed rod *r* having a button

at the exterior of the lamp. This rod *r* is adapted to engage the lower end of the lever *o* but is not linked to the same, in order to enable the housing *b* with the whole igniting 45 device to be withdrawn from the lamp, by simply withdrawing the rod *r* from engage- ment with the same. The guide plate *k* serves to guide the spark produced to the mouth of the burner *n* to ignite the gas es- 50 caping therefrom. The friction between the plate *l* and the body *i* is caused by the action of the spring *p*, which pulls the lever *o* rapidly back to its initial position, after the rod *r* and button have first been depressed 55 inwardly and then released.

The present igniting device may be used in connection with miners' lamps or safety locomotive lamps and the details of con- struction might be varied in many ways, 60 without departing from the nature of the present invention.

I claim as my invention:—

In a pyrophoric ignition device for miners' lamps, comprising a downwardly 65 extending spring pressed pyrophoric body and a spring-returned roughened metallic surface to contact with the same, the com- bination of a casing, a lever mounted there- in, a pivot to support said lever, a roughened 70 arm of arc shape struck from the center, means for retaining the said arm against the pyrophoric body and a spring pressed pin to operate said lever from the outside of the lamp. 75

In testimony whereof I affix my signature in the presence of two witnesses.

ANTON PASIERBSKI.
